US0D1060317S

(12) **United States Design Patent** (10) **Patent No.:** **US D1,060,317 S**
(45) **Date of Patent:** **** Feb. 4, 2025**

(54) **MICROPHONE AND RECEIVER KIT**

(71) Applicant: **Dongguan Zengyang Electronic Technology Co., Ltd.**, Guangdong (CN)

(72) Inventor: **Wenyang Shen**, Hunan (CN)

(73) Assignee: **Dongguan Zengyang Electronic Technology**, Dongguan (CN)

(**) Term: **15 Years**

(21) Appl. No.: **29/965,720**

(22) Filed: **Sep. 28, 2024**

(30) **Foreign Application Priority Data**

Jul. 15, 2024 (CN) 202430439978.2

(51) **LOC (15) Cl.** **14-01**

(52) **U.S. Cl.**

USPC **D14/225**

(57) **CLAIM**

The ornamental design for a microphone and receiver kit, as shown and described.

DESCRIPTION

FIG. 1 is a perspective view of a microphone and receiver kit showing the new design;

FIG. 2 is a front perspective view of the microphone thereof, shown separately for ease of illustration;

FIG. 3 is a second perspective view thereof of FIG. 2;

FIG. 4 is a front view of FIG. 2;

FIG. 5 is a rear view of FIG. 2;

FIG. 6 is a left side view of FIG. 2;

FIG. 7 is a right side view of FIG. 2;

FIG. 8 is a top plan view of FIG. 2;

FIG. 9 is a bottom plan view of FIG. 2.

FIG. 10 is a perspective view of the receiver of the microphone and receiver kit thereof, shown separately for ease of illustration

FIG. 11 is a second perspective view thereof of FIG. 10;

FIG. 12 is a front view of FIG. 10;

FIG. 13 is a rear view of FIG. 10;

FIG. 14 is a left side view of FIG. 10;

FIG. 15 is a right side view of FIG. 10;

(Continued)

FIG. 16 is a top plan view of FIG. 10; and, FIG. 17 is a bottom plan view of FIG. 10. The broken lines depict portions of the microphone and receiver kit that forms no part of the claimed design.

1 Claim, 17 Drawing Sheets
